Primary Examiner — Sandra Snapp(74) *Attorney, Agent, or Firm* — Diana Mederos; Mederos Legal, PLLC(57) **CLAIM**

The ornamental design for an electronic device clip, as shown and described.

DESCRIPTION

FIG. 1 is a front perspective view of an electronic device clip according to the present invention;

FIG. 2 is a front view of the electronic device clip of FIG. 1;

FIG. 3 is a bottom view of the electronic device clip of FIG. 1;

FIG. 4 is a left side view of the electronic device clip of FIG. 1;

FIG. 5 is a right side view of the electronic device clip of FIG. 1; and,

FIG. 6 is a rear view of the electronic device clip of FIG. 1.
